CHARLES G. RICHARDSON, OF SPRINGFIELD, VERMONT, ASSIGNOR TO PARKS & WOOLSON MACHINE COMPANY, OF SPRINGFIELD, VERMONT, A CORPORATION OF VERMONT

MACHINE FOR APPLYING TRANSFER STAMPS TO FABRIC

Application filed October 12, 1927. Serial No. 225,784.

This invention relates to the art of applying decalcomania or transfer stamps to cloth either for the purpose of trade-marking the goods or for applying yard-marking numbers or the like to various kinds of fabric, and is intended to provide a mechanism which will be particularly suited to the peculiar requirements of a machine doing this work.

I find in practice that it is highly desirable, to get the best results when hot-pressing or stamping such transfer stamps on a fabric, that there shall be a complete absence of rubbing or rolling contact between the platen and its cooperating presser, while at the same time it is desirable that the machine should operate at considerable speed in order to facilitate the marking of large quantities of fabric without loss of time and at small cost of operation.

One of the principal characteristics of the machine forming the subject matter hereof is the combining of a rotary drum, provided with a flat or truncated portion tangent to the circle of revolution, with an opposing revoluble element having a flat presser arranged so that the two opposing flat presser surfaces may continuously revolve in contact with each other, during the transfer operation, thus avoiding the tendency toward rubbing that is incidental to the use of a revolving cylinder surface, while permitting rapid operation of the machine.

Other features that are characteristic of the present improvement relate to the controlling of the feed of the tape bearing the transfer stamps and the disposal thereof after the stamps have been impressed upon the fabric, with the minimum of trouble and inconvenience, including the heating of the tensioning rolls which draw the tape over the pressing bed or platen, and the preliminary heating of successive transfer stamps before they reach the platen or presser bed in order to soften the stamps before they are impressed upon the fabric, thereby avoiding the use of a scorching heat in the presser operation. These and other features of the invention will be described in the following specification and will be defined in the claims hereto annexed.

In the accompanying drawings:

Figure 1 shows a front elevation of the tape-feeding and transferring drum partly broken away to show the tape-supplying reel, the feeding and drawing off mechanism in association with the flat revolving pressed bed. 55

Figure 2 is a rear elevation of this drum.

Figure 3 is a detail view showing, in front elevation, the relation of the tape-uncoiling and feed rolls by which the transfer tape is fed to the platen by regulated and accurately controlled feed. 60

Figure 4 is a plan view of the drum showing the truncated cut away portion of the periphery with the interior mechanism and the draft rolls for disposing of the waste tape. 65

Fig. 4^a is a detail view in side elevation showing one of the side arms of a tape carrying reel and its means of attachment to the reel shaft. 70

Figure 5 is a cross sectional view of the variable circumference feed roll.

Figure 6 is a detail view showing the stationary feed-actuating cam and the commutator through which passes the electric current used for the heating elements carried by the revolving drum. 75

Figure 7 is an end elevation of the drum and its co-acting presser in operative position to press the transfer stamp against the fabric.

Figure 8 is a detail showing, in front elevation, the revolving presser. 80

Figure 9 is a central section through the presser.

Figure 10 is an end elevation of the reel and the tape-drawing off mechanism. 85

Figure 11 is a detail view principally in vertical cross section of the frictional drive adjustment used for setting the final draft rolls in proper position to bring a transfer stamp into proper registry with the presser above the platen or bed. 90

Figure 12 is a view of the expandible chuck which serves as a clutch to grip the sprocket driving chain equipped for feeding the tape. 95

Fig. 13 is a diagrammatic view illustrating the electric circuits for heating the platen and the draft or tensioning rolls that draw the tape across the platen.

As decalcomania stamps are preferably applied at precise intervals along the length 100

of the cloth and as, particularly in the case of yard marking and numbering by decalcomania stamps, it is essential that this spacing be very exact, provision has to be made for very accurate feeding of the tape to those points on the cloth where the successive stamps are to be applied. Furthermore, as the transfer stamp tape is coiled into a roll, and as the stamps are rather gummy or sticky, it is desirable that provision should be made for stripping or unwinding sufficient length of tape from the coil without putting unnecessary tension on the feed roll which controls the delivery of previously determined lengths of tape to the presser elements which apply the stamps to the cloth. Moreover, since the drum, that carries the tape and the mechanism, must revolve quite rapidly in order to do its work expeditiously, the tape should be held taut until it has passed beyond the point of transfer. To effect this, pull or draft rolls, beyond the platen where the transfer takes place, must be properly co-ordinated with the controlling delivery-roll which determines the rate of feed. Furthermore, adjustment has to be provided by which the tape may be drawn through the machine to such a position that the successive stamps will exactly register with the same point of transfer on the platen, and provision is also made, in case of any departure from this exact registry, to re-set or re-adjust the driving mechanism to restore the exact register of the successive transfer stamps with the point of transfer on the platen. The draft rolls must also function without having their action impaired through becoming sticky through the adhesion of the gum on the stamps to their surfaces.

In the practice of this invention, according to the form illustrated in the drawings, I have devised constructions and arrangements which take full cognizance of all these requirements, and I will now describe the details of construction illustrated in the drawings.

Except for the stationary cam 7, mounted upon the fixed hollow bearing member 7^a, the working parts of the apparatus are carried by a revoluble drum comprising a cylindrical metallic shell 1, one sector of which is cut away lengthwise of the drum to provide for the mounting of a flat surfaced platen 4, which forms, at this point, a truncated or flattened continuation of the cylindrical shell. This flattened or truncated part of the drum is continued toward the middle by means of a flat plate 44 which, in conjunction with upturned flanges 44^a, forms a guiding platform over which the paper-transfer tape travels toward the platen. Above the flanges is placed a cross strip 45, which forms a cover to prevent the outward bulging of the tape at this point when the drum is revolving. Both the platen and the guide-

plate 44 are provided underneath with electric heating cartridges or units 4^b and 44^b, the latter serving as a preliminary heater to soften the transfer stamps so that it is not necessary to have a scorching heat on the platen in order to satisfactorily effect the transfer of the stamp by pressure to the cloth. 70

I will now describe the mechanism by which the accurate feeding of the tape is 75 accomplished.

Mounted about a transverse axis on the end of the drum, in position to mesh with the stationary helical cam 7, is a revoluble spur-gear 8 so co-ordinated with the helical cam or screw that one revolution of the drum operates to rotate this spur-gear one tooth in the direction of the arrows shown in Figures 1 and 2. 80

As shown in Figure 7, the spur-gear 8 is compounded on a shaft with a pinion 9 which meshes with a pinion 10 that is splined to a short shaft or spindle 14, whose inner end is enlarged to form a head 15 that is split diametrically to form an expandible head or chuck, this head or chuck being conically bored at its center and being threaded to receive an expanding screw 13 which carries a roughened or milled head 13^a forming a hand-wheel by which the expanding stud may be forced farther into the expandible head or chuck 15 with its conical portion acting to expand the periphery of the head into frictional engagement with the interior face of a sprocket gear 12. In this way there is formed a releasable or easily disconnected drive connection between the shaft 14, driven by the pinion 10, and the sprocket wheel 12 over which passes a sprocket-chain 17^a extending lengthwise and interiorly of the drum to a sprocket 17 on the shaft of the tape-feeding roll 18. 95

The tape-feeding roll must be very accurately calibrated or adjusted in order to feed exactly the proper predetermined length of tape to the transfer point at each revolution of the drum in order that the successive transfer stamps on the tape may be made to accurately register with the point of application between the presser bed or platen and its co-acting revolving presser pad. Moreover, there must be no slippage on the controlling feed roll. To meet these requirements the controlling feed-roll is constructed to provide an accurate adjustment for giving it exactly the correct circumferential measurement, and this is accomplished by providing each of the end heads 18^b of this roll, that are secured to the shaft 18^c thereof, with volute or spiral grooves 18^e along their inside faces. A thin circumferential shell of sheet metal 18^d is drawn in to both spiral grooves and by its circumferential adjustment its periphery is set nearer to or farther from the central shaft or axis. Around the 100

periphery of this circumferential sheet is placed a rubber tube 18^c which will expand or contract, according to the adjustment of the circumferential member as above explained.

Not only is the individual governing feed-roll provided with the adjustment described, but provision is made for the quick and convenient substitution of feed-rolls of different sizes since the spacing of various transfer stamps on the tape will vary much more than the practicable range of adjustment of one cylinder will compensate for. To this end, as shown in Figure 4, one end of the roll-shaft 18^a is formed with a bearing socket to receive the bearing stud 18^f carried on a pivotal arm 18^g which is normally pressed toward the roller by a coiled spring 18ⁱ. At the opposite end of the roller the square end of the shaft projects into the socketed end of a short shaft 18^m. Obviously, the pushing of the bearing member and its cap-supporting arm 18^g outward allows the opposite square end of the shaft 18^a to be withdrawn from the socket in the short spindle 18^m without loss of time to permit the quick substitution of a properly calibrated roll to be used in connection with a differently spaced transfer tape.

A cooperating feed roll 19 is mounted below the controlling feed-roll 18, said idler roll 19 being mounted in pivotal arms 20 by which the outer roll 19 is yieldingly pressed against the underside of the feed roll 18, this pressure being induced by a tensioning spring 21 secured to the cross-bar 20^a which connects the short arms of these levers.

The tape-carrying reel with its stripping or unwinding mechanism is of novel construction and is intended to obviate troubles that might result from the adhesion of one layer of tape in the coil to another to maintain a substantially uniform but light tension upon the tape that is being delivered from the reel to the regulating feed-roll 18. Provision is also made for quickly and conveniently removing the reel from its bearing supports in order to introduce fresh spools of tape. It will be understood that the tape-carrying reel is frictionally and intermittently driven and that it is coordinated with a stripper or pull-off device which draws off predetermined lengths of tape and maintains tension thereon, the stripper device being so related to the revoluble reel that when a sufficient supply of tape has been drawn off at any given time the reel is locked or held against rotation, thus permitting the unwound stretch of tape to be maintained under tension until such length of tape has been taken up by the feed-roll, at which time the revoluble reel is released and the stripper again performs its unwinding or drawing off function.

The reel comprises a central shaft 27

which is externally threaded practically throughout its length, and over which are slipped centrally bored tape-gripping arms 31 which are slidably axially on the shaft but are keyed thereto by short keys 31^b inserted in the longitudinal key-way in the shaft, and having their projecting edges sharpened to slightly cut into and grip a spool barrel on which the transfer tape is coiled in order to prevent circumferential slip of the tape-spool on the shaft or spindle 27. Furthermore, the inside faces of the heads or arms 31 are roughened or burred as at 32 to frictionally grip the spirally wound edges of the tape-coil to hold them against displacement.

Outside of the head 31 are mounted, on the shaft 27, internally threaded disks or nuts 33, provided with an overhanging boss carrying a set-screw 33^a which can be turned inwardly to firmly engage the exterior hubs 31^a of the arms or spiders 31.

One end of the shaft 27 is made square or polygonal to fit into a corresponding socket formed in the short shaft 27^b which is supported in coaxial alignment with the shaft 27, and which carries fast thereon a driving sprocket 24 connected with a sprocket 23 on the section 18^m of the feed-roll shaft by means of a sprocket chain 24^a so as to be driven therefrom. There is also loosely mounted on this short shaft 27^b a ratchet-wheel 26 whose outer face frictionally engages the friction pad 25 secured to the inside face of the sprocket 24 so that the ratchet is frictionally driven, and when rotated communicates its rotation to the reel through the shaft 27. A thrust-spring 34, at the opposite end of the shaft, acts not only to keep the polygonal end 27^a of the shaft 27 pressed into its engaging and driving socket, but also exerts a thrust which creates a pressure between the ratchet 26 and the friction driving pad 25.

Extending beyond the reel is a pivotal frame comprising vertical arms 28, a cross-connecting rod or roller 28^a joining their upper ends, and a rock-shaft 28^b joining these arms near their lower ends but at a short distance therefrom to leave the short arm 28^c to which is attached a tensioning spring 28^d anchored to a fixed pin in the frame end tending to force the tape-engaging roller or bar 28^a away from the reel. One arm 28 of the stripper device carries a pivotal link 28^e which has pivotal engagement with a pawl 30 supported on a fixed fulcrum to engage the ratchet 26 when the stripper frame 28, 28^a is swung away from the reel. As will be best understood by referring to Figure 3, the tensioning spring 28^d normally tends to swing the stripper frame backward or away from the reel, but when that frame approaches its rearward limit of traverse the pawl then becomes engaged with the ratchet teeth 26, thus preventing unwinding rotation of the reel and main-

taining the bight or stretch of tape between the reel, the stripper and the feed-roll 18 under a light tension to keep it taut. The feed roll 18 continues to draw off the tape for 5 delivery to the transfer pressers, and in so doing gradually pulls forward the stripper frame 28 until the pawl 30 becomes disengaged from the ratchet. When this happens the stripper is again retracted by its actuating spring to strip off or uncoil a further supply of tape from the reel, whose friction feed is then allowed to operate.

The tape passing over the top of the feed-control roll 18 and around the idler roll 19, 15 as shown in dotted lines in Figure 1, thence passes over guide-plate 44 beneath the cover 45 to the heated presser plate or platen 4 where it is pressed against the fabric by means 20 of a revolving presser pad, presently to be described. It is, of course, important that this stretch of the tape also be kept taut to prevent wrinkling and, accordingly, revoluble draft rollers 41, 42, located just beyond the platen 4, are employed to draw the tape forward and 25 keep it taut. These draft rollers are driven by a frictional drive to avoid exerting too positive a pull upon the tape that is delivered at a predetermined rate from the feed-roll 18. These draft rollers 41, 42, are made hollow 30 for the reception of electrically heated cartridges 41^a and 42^a so as to soften any gum from the stamps adhering thereto and allowing it to run off. Preferably these rolls are 35 longitudinally corrugated and the corrugated portions are interrupted by frequent annular grooves the annular grooves on one roll being offset from the planes of the annular grooves of the other roll so that the annular grooves 40 provide channels into which the softened gum may flow from the narrow corrugated portions of the roll. This construction and arrangement prevents the accumulation of gum on the rolls which might cause the adherence 45 of the tape in such a way as to interfere with the proper draft of the rolls on the tape. Electrical wires 37 lead to the heating cartridges 38 inserted in the rolls which are in 50 circuit with the preheating cartridge 44^b, arranged beneath the guide-plate 44, these heating elements being included in a different circuit from the heating elements 4^b that are 55 inserted in the heated platen 4.

The corrugations of the two rolls 41 and 55 42 intermesh with each other so that the upper roll is driven from the lower one. The lower roll carries, at one end, a driving pinion 40, meshing with a pinion 39 mounted loosely 60 on the shaft or arbor 35. This pinion 39 is frictionally driven by lateral contact with the friction disk 16^b which is integral with the sprocket wheel 16 and with the hand-adjusting nut 16^e. A spiral spring 16^a, abutting 65 against a thrust nut on the end of the arbor 35, keeps the sprocket friction element pressed against the face of the driving pinion 39.

The sprocket wheel 16 is engaged and driven by the sprocket chain 17^a, so that the draft rolls, the feed roll and the unwinding reel are all driven from a common driving element, namely, the worm-gear 8.

Since it is desirable that the feeding of the tape should momentarily cease while the tape is being pressed against the fabric between the presser members, the stationary cam 7 has an intermediate straight line portion without inclination, as shown at 7^b, this being so co-ordinated that the worm-gear is passing over this straight line portion of the worm 7 during the transfer operation in which the individual transfer stamp is hot-pressed up 80 on the fabric.

The revolving presser pad that co-acts with the flat platen 4, to impress each tape carried stamp upon the fabric, is mounted on a counter-shaft 50 which is parallel or substantially so with the axis of revolution of the drum 1, over which the cloth travels, and comprises an arm 51, provided with a bore 51^a, which is split to permit it to be clamped upon the revolving shaft 50 to revolve therewith. The radial arm 51 is bored lengthwise to receive a plunger 52 which is normally thrust out under the yielding pressure of a thrust-spring 53, the outward movement being limited by a stop pin 54 engaging a slot 52^a in the plunger. The outer end of the plunger 52 is slotted for the insertion of a shoe 55, whose opposite ends are turned up at an angle to form a heel and toe to act as a runner to properly guide the shoe which is pivoted in the slotted end of the plunger in its movements. To the underside or outside of this shoe is secured a flat presser plate or pad 56. The forward or toe end of the shoe 55 is normally tilted toward its axis of rotation by means of a tensioning spring 57 attached to the short end of a rocker-arm 58 whose opposite end or long arm is connected by a link 59 to the shoe 55.

In order to vary the position of the stop-pin 54, a sleeve 51^b, is adjustably clamped on the outer end of the arm 51. The adjustment of this sleeve determines the outermost limit of movement of the plunger 52. The anchored end of the spring 57 is anchored to a clip 57^a 110 attached to this sleeve 51^b.

It will, therefore, be seen that the presser pad 56 has a pivotal or rocking movement with relation to the outer end of the plunger, which itself can move in a radial direction 120 with relation to its axis of rotation. The object of this arrangement is to produce an effective pressure between flat presser surfaces to press the transfer stamp or tape firmly against the cloth, and maintain such pressure for a brief interval between the flat surfaces while both the presser elements are revolving.

The pressure between flat plates is the most effective for getting a clear, distinct and unblurred impression of the transfer stamp.

The maintenance of that pressure for a very brief interval is desirable for the purpose of effectually impressing the stamp on the cloth. By the peculiar rocking and yielding motion the pressing is effected between two parallel plates in a position substantially perpendicular to the plane intersecting and including their two axes of rotation, and this without producing any rubbing action that would tend to blur the impression of the stamp. 5 This co-ordinated movement of the two pressers is further facilitated by the use of intermeshing elliptical or eccentric gears 61, 62, which compensate for the variable ratios of 10 revolution of the flattened areas of the two presser members since different portions of the flat surface of the platen *a* are located at different radial distances from the axis of revolution, while the same thing is true of the pivotal presser pad which cooperates with it. 15 When the parts are in the position of the parts shown in Figure 7, both presser elements should be rotating at exactly the same rate of travel, and in that position those teeth 20 of the two elliptical gears that are located at equal radial distances are then intermeshing. It will be observed that while the traveling tape has a pause during the pressing operation, the cloth travels continuously with the 25 continuously revolving drum at right angles to the travel of the tape so that there is no interruption in the feed of cloth which can be fed through the machine very rapidly, while still permitting the perfect transfer impressions thereon.

This stamp-transferring drum will usually be used in conjunction with a cloth-measuring machine or a cloth-winding and measuring machine. The drum is supported by central axially aligned trunnions at each end, only one of which is shown, namely, the driving trunnion which passes through the hollow bearing 7^a which carries the fixed cam 7. This hollow trunnion or shaft 65 forms a conduit 40 for leading the electric current to the heating elements carried by the drum, and for this purpose ordinary commutator rings 66, engaging the brush terminals 67, carried by the stationary bearing frame 7^a, to which the lead-in wires are connected, serve to permit the rotation of the drum, while maintaining the necessary electrical connections. The trunnion shaft 65 also carries a driving 45 sprocket 68 by which the drum is rotated at the desired speed.

What I claim is:

1. In a stamp transferring machine, the combination of two co-acting flat faced presser members, each revoluble about a single 50 separate axis that is substantially parallel to the axis of the other to imprint a transfer stamp upon an interposed fabric, said presser members being arranged to exert opposed pressure between the flat surfaces while the 55 presser members are revolving.

2. In a stamp transferring machine, the combination of a continuously revoluble cloth-engaging and feeding drum, drum-supported tape-feeding means for delivering intermittently predetermined lengths of stamp-bearing tape at each revolution of the drum, co-acting flat presser members arranged to revolve in opposition to each other about spaced parallel axes, to press together interposed portions of the traveling cloth and of the tape while both members are in revolution. 70

3. In a stamp transferring machine, the combination of two flat surfaced presser elements mounted to revolve in opposition to each other about two spaced parallel axes to press together between them, while revolving, a transfer stamp and a predetermined portion of the cloth to be stamped, said members being interconnected by driving means varying their relative speeds in different parts of their revolution, thereby maintaining a non-slipping pressure of both flat surfaces as they approach and recede from their positions perpendicular to the plane containing both axes of revolution. 80

4. In a stamp transferring machine, the combination of a revoluble cloth-engaging drum, a flat faced pressure-resisting platen mounted thereon to form a truncated sector of the drum periphery over which the cloth travels in a circumferential direction, a flat presser pad mounted to revolve outside of and in opposition to said platen about an axis parallel to the drum axis, said pad being pivotally mounted on a supporting arm to allow it to accommodate itself to parallel relationship with the flat surface of the platen, thereby pressing an interposed transfer stamp against an interposed portion of the cloth while both platen and pad are revolving in pressing relationship. 95

5. In a stamp transferring machine, the combination with a revoluble flat faced presser platen, a coacting flat faced pressing pad yieldingly and pivotally supported at the outer end of an arm that revolves about an axis disposed at a distance from and parallel with the axis of revolution of the drum, and means coordinating the rotation of the platen and of the drum to vary their relative speed ratios as the platen and the pad approach and recede from the line intersecting their respective centers of revolution. 110

6. A revoluble presser member for exerting pressure against an opposed revolving flat faced platen, embracing in its construction an arm adapted to be secured to a rotary shaft to project outward therefrom, a spring-pressed plunger mounted on said arm and having limited movement radially of the shaft, a presser pad pivotally connected to the outer end of said plunger and having a flat outer pressing face arranged to be pressed against the flat face of the platen in parallel- 125 130

ism therewith while the two flat surfaces are revolving in opposition to each other.

7. A revoluble presser member for exerting pressure against a flat faced platen revolving in opposition thereto, embracing in its construction a revoluble arm variable as to radial length in response to endwise pressure, and a pivotal presser pad connected to the outer portion of said arm and by its pivotal and yielding support acting to accommodate itself to parallelism with the flat face of the platen as they revolve in opposed pressing relation to each other.

8. A revoluble presser element for maintaining a stamp-transferring pressure against an opposed revolving flat faced presser platen, embracing in its construction a radially extensible and contractible arm adapted to be secured to a rotary shaft, a flat faced presser pad pivotally mounted at the outer end of said arm to have a limited rocking movement permitting it to adjust itself to parallel relation with a cooperating revolving flat faced platen, and a spring acting normally to retract the forward end of the pad in advance of its pivotal center nearer to its axis of rotation, and guide members extending beyond the ends of the pad.

9. A presser element for exerting pressure between two flat surfaces revolving about separate parallel axes, embracing a revoluble arm of variable radial length and a flat presser pad pivotally attached to its outer end, and means for revolving said arm about its axis of revolution at variable speeds in different parts of its orbital movement.

10. The combination of a continuously revoluble cloth-engaging drum, a flat presser platen mounted peripherally thereon, a revoluble stamp-bearing tape roll, means for intermittently stripping lengths of tape from the reel and maintaining said strip portions under tension, a feed-controlling delivery roll for delivering predetermined lengths of tape to the platen, means for pressing the transfer tape and a predetermined portion of the cloth against said platen to impress a stamp upon the cloth, and co-ordinated means for drawing the used portion of the tape away from the platen.

11. The combination with stamp-transferring pressers one of which is mounted on a revoluble cloth-feeding drum to revolve therewith, of means for feeding successive transfer stamps arranged on a continuous tape to transfer position between the pressers, said feeding means comprising a revoluble tape-carrying reel, an intermittently actuated stripper and tensioning member, and an intermittently actuated feed-measuring delivery roll, and means for keeping the tape leading from the delivery roll over the drum-supported presser in taut condition.

12. The combination with a revoluble cloth drum and revoluble stamp-transferring

pressers, of means for delivering successive stamps of a stamp-bearing tape to transfer position between said pressers said delivering means having feeding engagement with the tape both in advance of and beyond the transferring position of said pressers at each successive revolution of the drum, means for actuating said delivering means, said actuating means being operated by means of the rotation of the drum.

13. The combination with a continuously revoluble cloth drum and revoluble stamp-transferring presser, of co-acting means arranged on both sides of the pressing position for delivering successive stamps on a stamp-carrying tape to transfer position between said pressers at each revolution of the drum, intermittently acting means for actuating said stamp-delivering means, said actuating means being operated by means of the continuously rotating drum.

14. In a stamp-transferring machine, the combination with a revoluble cloth drum and a pressing platen mounted thereon to support the thrust of a coacting presser pad, means for successively feeding between said pressers a series of transfer stamps carried on a continuous tape, said feeding means comprising a revoluble supply reel, a vibratory stripper for drawing off said reel and maintaining, under tension, predetermined lengths of said tape, a feed-controlling delivery roll and draft rolls located beyond the platen to keep the tape supplied by the delivery roll taut, the reel being frictionally driven to allow interruption of its revolution when the stripper has drawn off therefrom a predetermined length of tape.

15. The combination with a revoluble cloth-supporting drum and a presser platen mounted thereon to receive the thrust of a coacting presser pad, of means for delivering successively to said pressers transfer stamps carried on a continuous tape, said means comprising an intermittently revoluble reel, a vibratory tensioning stripper, a positive feed roll and frictionally driven draft rolls.

16. The combination with a revoluble cloth-supporting drum and a presser platen secured thereon to receive the pressure of a cooperating presser pad, of means for delivering measured lengths of stamp-carrying tape to transfer position between the pressers, said means including a frictionally surfaced feed roll adjustable as to circumference, and a pair of frictional draft rolls located beyond the platen and acting to keep taut over the platen the intermediate stretch of tape, and rotary actuating means for rotating the feed roll, said actuating means remaining at rest during the tape-pressing interval.

17. In a stamp-transferring machine, the combination with a continuously revolving cloth drum, a presser platen mounted thereon, means for feeding to the platen measured

lengths of a transfer-stamp carrying tape, a rotatable feed-actuating gear mounted on said drum, a stationary gear-actuating worm positioned to engage said actuating gear to rotate it by means of the rotary movement of the drum.

18. In a stamp-transferring machine, the combination with a continuously revolving cloth drum, a presser platen mounted thereon, means for feeding to the platen measured lengths of a transfer-stamp carrying tape, a rotatable feed-actuating gear mounted on said drum, a stationary gear-actuating worm positioned to engage said actuating gear to rotate it by means of the rotary movement of the drum, said worm having intermediate of its ends a straight portion which, when engaged by the actuating gear, holds the gear temporarily at rest to prevent feeding the tape during the transfer operation.

19. In a stamp-transferring machine, the combination with a revoluble cloth drum, a heated platen secured thereto a coacting presser pad for pressing an interposed transfer stamp against the cloth on the platen, tape-feeding means for feeding a stamp-transfer tape to transferring position between the pressers, and a preheating device arranged in proximity to the tape in advance of the platen to soften the stamps successively passing near it before they reach the transfer position over the platen.

20. In a stamp-transferring machine, the combination with a revoluble cloth drum, of a presser, a heated platen secured to the drum to receive the pressure of the coacting presser, means for feeding measured lengths of a transfer-stamp carrying tape to transfer position over the platen, said feeding means including heated draft rolls for drawing the tape beyond the platen and removing the gummy residue of the used transfer stamps therefrom.

21. Degumming draft rolls for a transfer-stamp tape embracing longitudinally corrugated intermeshing rolls provided with annular grooves, the grooves of one roll being axially offset with relation to those of the other roll.

59. In witness whereof, I have subscribed the above specification.

CHARLES G. RICHARDSON.
